UNITED STATES PATENT OFFICE

ROBERT B. POGUE, OF CHICAGO, ILLINOIS, ASSIGNOR TO THE AMERICAN BRAKE SHOE & FOUNDRY COMPANY, OF WILMINGTON, DELAWARE, A CORPORATION OF DELAWARE

BRAKE SHOE

Application filed February 14, 1931. Serial No. 515,654.

This invention relates to brake shoes of the kind which are often referred to as "composition shoes" or "filled shoes" and comprise a metal shell containing a friction composition body. The body is held in place by the sides and ends of the shell which are sometimes provided with openings to receive the body material for anchoring the body in the shell. The pressure and friction heat in service applications of the brake shoe in the ordinary use thereof sometimes cause the sides of the shell to bulge or otherwise become distorted so that the body will no longer be rigidly and securely held in the shell and when this happens the body is liable to break down and fall away.

It is the object of my invention to more securely hold the body in the shell by reenforcing and strengthening the shell so that it will maintain its shape throughout the period of use of the shoe.

Another object of the invention is to maintain the sides of the shell in parallelism during the period of use of the shoe by means of transverse braces which are so arranged and disposed that they will not weaken the body.

And a further object of the invention is to provide a novel construction of the shell to assist in the formation of the end and guide lugs and to reenforce and strengthen the same.

In the accompanying drawing I have illustrated the invention in a selected embodiment and referring thereto,

Fig. 1 is a longitudinal central section view of a brake shoe embodying the invention.

Fig. 2 is a plan view showing the back of the shell.

Fig. 3 is a plan view showing the inside of the shell.

Fig. 4 is a detail sectional view on the line 4-4 of Fig. 2.

Fig. 5 is a transverse sectional view on the line 5-5 of Fig. 2.

Fig. 6 is a transverse sectional view of a flanged shoe embodying the invention.

Referring to the drawing, the shell is stamped out of sheet metal and comprises a back 7, sides 8, 8 and ends 9, 9. The back of the shell is preferably provided with corrugations or flutes 10 extending lengthwise of the back to increase the stiffness and rigidity thereof.

The sides of the shell are provided with openings 11 to receive the body material 12 for anchoring the body in the shell. The ends 9 of the shell may likewise be provided with openings 11 if desired. The edges 13 of the sides of the shell may be scalloped as shown in Fig. 4 if desired. Cross braces 14 are arranged within the shell and the ends 15 of the braces are bent to lie snugly within and against the sides of the shell to which they are rigidly secured by spot-welding or other suitable means. The shell is arcuate and the braces are narrow metal strips extending transversely in a direction generally radial of the arc of the shell. The ends of the braces 15 may be enlarged to form ample bearing against the sides of the shell and to accommodate whatever securing means may be employed. Any number of these braces may be provided as shall be found necessary or desirable; and when two are employed I prefer to arrange them substantially midway between the attaching lug 16 and the ends of the shell. The braces for an unflanged shoe, as shown in Figs. 1-5, are preferably abutted 70 against the corrugations or flutes 10 which space the braces away from the back of the shell, Fig. 5. It is not necessary that the braces should be fastened except at their ends to the shell, Figs. 1-5, but in the flanged type of shoe as shown in Fig. 6, it is desirable to fasten the braces between their ends to the shell as well as at their ends, and referring to Fig. 6 I have shown the brace 17 provided with the enlarged ends 18 which are fastened to the shell as hereinbefore explained, and also with lugs 19 which are spot-welded or otherwise fastened to the shell opposite the tread of the shoe and in the flange of the shell. These additional fastening means ensure maintaining 80 the brace in rigid position while the body material is being pressed into the shell and during the subsequent service use of the shoe. A transverse slot 20 is cut in the back adjacent each end of the shoe and the metal stamped out in forming this slot is pressed up to form the high inner flanges 21 and the low outer flange 22, the inner flanges being spaced apart at 23. Flanges 24 extending lengthwise of the shell are stamped from the back thereof to 100

form an opening 25 which communicates through the space 23 with the slot 20. The flanges 24 abut the flanges 21 and the body material is permitted to flow up through the 5 slot 20 and the opening 25 to form the end lug 26 and the side lug 27 which are integrally connected by the body material in the space 23. Thus the end lug is faced on its inner side by the flanges 21 and the guide lug 10 is faced on its sides by the flanges 24, these flanges forming wear surfaces to receive the brake head to which the shoe is applied. The provision of the slots 20 and openings 23 and 25 to permit the body material to flow and seat 15 therein and form the end and guide lugs, provides an additional anchorage for the body in the shell and the composition material of these lugs serves to support and reenforce the wear and facing flanges 21 and 24. The up- 20 turned flange 22 at the outer edge of the end lug also assists in reenforcing and supporting the end lug.

In the manufacture of the shoe, the composition body material is molded in the shell 25 under sufficient pressure to form a solid compact body and the body material flows into the openings of the shell to anchor the body in the shell. The body material may flow between the braces and the back intermediate of 30 the corrugations or flutes and the sides of the shell and this provides an additional anchorage for the body in the shell. The body is subjected to severe end thrust strains in actual 35 service which naturally have a tendency to loosen the body in the shell and break down the body and cause it to disintegrate or fall away from the shell. The transverse braces help to resist the strains of brake applications 40 on the body besides holding the sides of the body rigidly in position while the body is being pressed into the shell and during subsequent use of the shoe.

I have described the shell as made of sheet metal and the body as made of a friction composition but I do not restrict the invention to 45 these materials or to the particular construction and arrangement of parts and reserve the right to make any changes therein within the scope of the following claims:

50 I claim:

1. A brake shoe comprising a shell and transverse braces secured within the shell and spaced from the back thereof.
- 55 2. A brake shoe comprising a shell having longitudinally extending corrugations in the back thereof, and transverse braces secured within the shell and abutting said corrugations.
- 60 3. A brake shoe comprising a shell and a body secured therein, said shell having a transverse slot and an opening connected therewith to receive body material for forming the end and guide lugs, and flanges struck 65 up from the back of the shell and forming

wear facings for said lugs to engage a brake head.

4. A brake shoe comprising a shell and a body secured therein, said shell having a transverse slot adjacent an end thereof to receive body material for forming the end lug, a flange at the inner edge of said slot forming a wear facing for the end lug to engage a brake head, the outer edge of the slot being turned up to form a flange to support the end lug. 70 75

5. A brake shoe comprising a shell, a composition body molded therein, and transverse braces connecting the sides of the shell and embedded in the body of the shoe spaced from 80 the wearing face thereof.

6. A brake shoe comprising a shell, a composition body molded therein, and transverse braces connecting the sides of the shell and embedded in the body of the shoe spaced from 85 the wearing face and adjacent the back thereof.

7. A brake shoe comprising a shell, a composition body molded therein, and transverse braces connecting the sides of the shell and embedded in the body of the shoe spaced from 90 the wearing face and the back thereof.

8. A brake shoe comprising a shell, a composition body molded therein, and transverse braces embedded in the body and having bent 95 ends extending longitudinally of the shoe and abutting the sides of the shell and rigidly secured thereto.

9. A brake shoe comprising a shell, a composition body molded therein, and transverse braces embedded in the body spaced from 100 the wearing face thereof and having enlarged ends extending toward the wearing face of the shoe and abutting the sides of the shell and rigidly secured thereto.
